F. NEUMANN

CENTRIFUGAL PUMP

Filed Nov. 9, 1923

F. Neumann

UNITED STATES PATENT OFFICE.

FRITZ NEUMANN, OF NUEREMBERG, GERMANY.

CENTRIFUGAL PUMP.

Application filed November 9, 1923, Serial No. 673,815, and in Germany November 13, 1922.

The connection of air pumps and centrifugal pumps, in such a manner that at the starting a vacuum is produced in the centrifugal pump with the aid of the air pump 5 whereupon the centrifugal pump is filled with liquid, is known per se.

The water ring pumps, e. g. pumps with circulating packing liquid, are especially adapted to be used as air pumps as they are 10 less sensitive against water hammers and submitted to a lesser wear than the usual piston pumps, the rotating piston pumps and the pumps with slide valves. For starting, a small quantity of water must be generally 15 filled into the water ring pump and in winter this water might freeze up so that the pump does not work. Water ring pumps could therefore hitherto not be used as air pumps for transportable pumps driven by 20 internal combustion engines, especially not for fire pumps.

This inconvenience is avoided according to this invention by taking the quantity of water, which is required for the permanent 25 readiness for service for the formation of the rotating liquid ring, immediately before the beginning of the service from the cooling liquid for the engine.

As the invention relates specially to 30 pumps designed for fire engines the air pump must not only be adapted to be used for the starting of the centrifugal pump but also, during the service, for exhausting the air which at great suction head will eventually separate in the suction pipe branch. The water ring pump must further be able 35 to be disengaged during the working of the centrifugal pump when the water flows under pressure into the suction pipe branch of the centrifugal pump. Fire engine pumps 40 must be able to work at great suction head as well as at water admission under pressure. These conditions are fulfilled in the most simple and efficient manner by arranging the 45 air pump on the same shaft as the centrifugal pump and in a common casing. In this case the machine aggregate is further of very compact construction.

In the accompanying drawings an embodiment of the invention is shown in

Fig. 1 in sectional elevation.

Fig. 2 shows the construction of the improved centrifugal pump with a combustion engine as used in fire engine pumps.

55 As shown in Fig. 1 the impellers of the centrifugal water pump are keyed on the

common shaft *d* on which the rotor *c* of the air pump is keyed on the suction side. The air pump and the centrifugal pump are arranged in a common casing which has a cooling jacket *b*. Two stuffing boxes *e*, that is not more than for an ordinary centrifugal pump, are used for the packing.

The water pump communicates with the air pump *c* through a ringshaped passage *k* 60 in the partition wall which separates the water pump from the air pump. An overflow *i* from the lowest point of the air pump *c* is normally closed by a cock *g*. The highest point *f* of the suction pipe branch of the water pump communicates through a point *k* in the partition wall with the air pump *c*. Above the pump casing a three way cock *a* is arranged from which leads a pipe *v* to a water reservoir *o* arranged on the engine, a 70 pipe *r* to the cooling jacket *b* and a pipe *w* to the highest point of the air pump *c*.

When starting the centrifugal pump the three way cock *a*, which may be connected or coupled with the control element which in fire engines is provided for the different conditions of service or with the element for the engaging or disengaging of the heating and cooling jacket *b*, is adjusted so that 80 communication between the cooling jacket *b* and the air pump *c* is established and it remains in this position until the quantity of liquid which is required for the starting of the water ring pump has flowed from the cooling jacket *b* into the water ring pump *c* 90 which then produces the vacuum in the centrifugal pump.

If the water ring pump continues to run after the starting of the centrifugal pump, the air which eventually separates in the suction branch pipe at great suction head is 95 sucked off through the passage *k*. In this manner a "scraping off" or a reduction of the delivery at great suction head is avoided.

If, however, as will generally be the case 100 with fire engines in towns, the water is supplied to the suction pipe branch of the centrifugal pump under pressure the air pump is not required. It would merely increase the demand of energy as it cannot be uncoupled but rotates with the centrifugal pump. Consequently the cock *g*, which may 105 also be coupled with other control elements, is opened whereby the air pump is emptied, which now does no longer rotate in the water 110 but in air and requires only very little energy. Any damaging of the air pump by

running dry is excluded as through the gap *h* which surrounds the shaft *d* a small quantity of water can always flow into the air pump and serve for the lubrication of this pump before it flows out.

- As shown in Fig. 3 the motor fire brigade vehicle comprises the centrifugal pump *m*, the water ring pump *n* and the water reservoir *o*. In a similar manner as in the first embodiment of the invention a pipe *r* adapted to be shut off by a three way cock *x* leads from the centrifugal pump to the water ring pump *n* so that this water ring pump can be fed at any time with cooling liquid from the combustion engine *s*. The water ring pump *n* is further connected with the water reservoir *o* by a pipe *v* adapted to be shut off by cock *x*. The water can therefore be supplied to the water ring pump either through the pipe *r* from the cooling jacket of the combustion engine *s* or through pipe *v* from the water reservoir, or, if cock *x* is adjusted accordingly fresh water is fed from reservoir *o* into the cooling jacket.
- The water pump is not in communication with the atmosphere through port *k* and cock *g*, when cock *g* is open, the water flowing out of the air pump fills this cock which is closed immediately after all the water has flowed out of the air pump. If cock *g* is closed the water pump is not open to the atmosphere through *k*.

I claim:—

1. The combination with a centrifugal fire engine pump, a water ring sealed air pump for priming said centrifugal pump, a driving motor operatively connected to said pumps for driving said pumps and a container for containing cooling water for said driving motor, of a pipe connected to said water ring pump and said cooling water container, for enabling hot water to be supplied from said container to said water ring pump for forming the liquid ring in the latter, as set forth.
2. The combination with a centrifugal fire engine pump, a water ring sealed air pump

for priming said centrifugal pump, a driving motor operatively connected to said pumps for driving said pumps, a container 50 for containing cooling water for said driving motor and a water reservoir, of a pipe connected to said water ring pump and said cooling water constructed for enabling hot water to be supplied from said container to 55 said water ring pump and a pipe connected to said water ring pump and said reservoir for enabling cold water to be supplied to the water ring pump from said reservoir, as set forth.

3. The combination with a centrifugal fire engine pump, a water ring sealed air pump for priming said centrifugal pump, a driving motor operatively connected to said pumps for driving said pumps, a container 65 for containing cooling water for said driving motor and a water reservoir of a three way cock, a pipe connected to said water ring pump and said three way cock, a pipe connected to said cooling water container 70 and said three way cock and a pipe connected to said reservoir and said three way cock, for enabling water to be supplied to the water ring pump from the said cooling water container or from said reservoir, or 75 from said reservoir to said cooling water container, as set forth.

4. The combination with a centrifugal fire engine pump, a water ring sealed air pump 80 for priming said centrifugal pump, a driving motor operatively connected to said pumps for driving said pumps, a container for containing cooling water for said driving motor, of a pipe connected to said water ring pump and said cooling water container 85 for enabling hot water to be supplied from said container to said water ring pump for forming the liquid ring in the latter, an outlet in the water sealed air pump at the lowest point thereof for enabling the water 90 to be emptied from said pump and a cock for closing said outlet, as set forth.

In testimony whereof I affix my signature.
FRITZ NEUMANN.
